UNITED STATES PATENT OFFICE

2,081,218

METHOD FOR STABILIZING MOTOR FUEL
AGAINST GUM FORMATIONRobert E. Burk, Cleveland, Ohio, assignor to The
Standard Oil Company, Cleveland, Ohio, a cor-
poration of Ohio

Application December 23, 1933, Serial No. 703,713

1 Claim. (Cl. 196—50)

In the customary methods of producing motor fuel by cracking petroleum, there is a formation of unstable gum-forming byproducts which subsequently require particular treatment if their results are to be avoided. Even this is not always wholly effective. I have now found however, how to produce motor fuel by cracking without the undue formation of gum-components.

To the accomplishment of the foregoing and related ends, the invention, then, comprises the features hereinafter fully described, and particularly pointed out in the claims, the following description and the annexed drawing setting forth in detail an illustrative embodiment of the invention, this being indicative however, of but one of the various ways in which the principle of the invention may be employed.

In said annexed drawing:—

The sole figure is a semi-diagrammatic elevational view of apparatus contemplated in the invention.

Cracking stock as desired, for example gas oil, is subjected to cracking which for desirable efficiency may be represented by subjection first 25 to a heating zone 2 and then to a digesting zone 3. From the digesting zone, in accordance with the present invention, the highly heated products proceed to a high pressure zone or drum 4 in which a high pressure is maintained and an ele- 30 vated temperature. For instance, the pressure may be 200-1500 pounds per square inch and the temperature 600-850° F. From the high pressure zone 4, the products pass through a pressure- 35 drop valve 5 to a tar separator 6. Vapors dis- engaged here proceed on through the fractionating zones 7, 8, and various cuts are taken off, and finally the motor fuel hydrocarbons pass from condenser 9 to receiver 10 which may have a pressure of 0-200 pounds per square inch. From 40 the receiver 10, all or a portion of the motor fuel condensate is returned by pump 11 to again enter the high pressure high temperature zone 4, there to mix with the other hydrocarbons in highly

heated condition, and under favorable conditions for inter-reaction. The motor fuel then finally taken off after the vapors have proceeded through the separator 6 and the fractionating zones 7, 8, and condenser 9, is found to have its gum-forming tendency checked, due apparently to reaction by the sensitive gum-forming parent substances. The motor fuel may be recycled one or more times as desired back through the high pressure zone 4.

As a further refinement of the invention, tarry 10 material or the like withdrawn from separator 6, or from the bottom of the high pressure zone 4 may be subjected to a vacuum stripping zone 12, from whence the vapors proceed through fractionating zones 13, 14, each taking out its respective fraction, and the motor fuel hydrocarbons as finally condensed in zone 15 proceed to receiver 16, all this portion of the system being under reduced pressure from the vacuum line 17 on the gas draw-off. Again, all or a portion of the 20 motor fuel hydrocarbons may be forwarded by a pump 18 back to recycle through the high pressure zone 4, one or more times as desired.

Other modes of applying the principle of the invention may be employed, change being made 25 as regards the details described, provided the features stated in the following claim, or the equivalent of such, be employed.

I therefore particularly point out and distinctly 30 claim as my invention:—

A process of gum-stabilizing motor fuel, which comprises heating heavy hydrocarbons to cracking temperature, digesting the hot hydrocarbons under pressure in an unheated zone, passing the products to a further pressure zone without tem- 35 perature increase, maintaining the products from such pressure zone in fluid state, then dropping the pressure, fractionating gasoline from the products, and passing such gasoline again through said pressure zone to contact with the hot freshly 40 cracked fluid products.

ROBERT E. BURK.
